UNITED STATES PATENT OFFICE.

WILLIAM A. THOMAS, OF CHARLESTON, OKLAHOMA.

HAME AND TRACE CONNECTOR.

1,177,975.

Specification of Letters Patent.

Patented Apr. 4, 1916.

Application filed July 20, 1915. Serial No. 40,924.

To all whom it may concern:

Be it known that I, WILLIAM A. THOMAS, a citizen of the United States, residing at Charleston, in the county of Harper, State 5 of Oklahoma, have invented certain new and useful Improvements in Hame and Trace Connectors; and I do hereby declare the following to be a full, clear, and exact description of the invention, such as will 10 enable others skilled in the art to which it appertains to make and use the same.

This invention relates to a hame and trace connector.

An object of the invention resides in the 15 provision of a device which may be readily attached to the ordinary trace bolt.

A further object of the invention resides in so constructing the device that the trace may be connected thereto at any of a plurality of points so that the line of draft 20 may be varied.

A further object of the invention resides in constructing the device of sheet metal so that it will be cheap to manufacture and 25 not readily broken.

With these and other objects in view, such as will appear as the description progresses, my invention comprises the combination and arrangement of parts as set 30 forth in and falling within the scope of the appended claim.

In the drawings: Figure 1 is an elevational view of my device showing the same attached to a hame; Fig. 2 is a sectional view on line 2—2 of Fig. 1; and Fig. 3 is 35 a view of the blank from which the device is formed.

In the embodiment of my invention shown in the drawing, the device comprises 40 a tubular bearing member 1 which is adapted to receive the trace bolt 2 which is mounted on the hame 3. Extending outwardly from this bearing member 1 are a plurality of arms 4, the ends of which are 45 bent to form eyes 5 for the reception of a bolt 6 which is removably mounted in the said eyes. A plurality of spaces 7 are formed between the arms 4 for the reception of the trace eye 8 which is shown in 50 the drawing as located in the lowermost space and as having the bolt 6 passing

therethrough. It will be readily understood that by the removal of the bolt 6 the trace eye may be inserted in any one of the spaces 7. The eye may be secured in these 55 spaces upon the replacing of the bolt.

As heretofore stated the device is made of sheet metal and the ends are wrapped about each other to form the bearing member 1.

In Fig. 3 of the drawing I have illustrated the blank from which the device is formed and this blank is of rectangular formation having a solid portion A at each end thereof which, when wrapped about each other form the bearing member. The 60 blank also includes a plurality of spaced strips B which are produced by the elongated openings C. These strips are bent, to form the arms and the eyes referred to in the description of the completed article. 70

From the foregoing description it will be seen that I have provided a hame and trace connector which is made from a sheet metal blank and consequently will be cheap to manufacture. I have so constructed the 75 device that it may be readily attached to a hame and so that the trace may be adjusted thereon.

While I have illustrated and described a particular embodiment of my invention it 80 has merely been for the sake of convenience and I do not wish to be limited to that particular embodiment as it is obvious that numerous changes may be made in the details of construction without departing 85 from the spirit of the invention or without exceeding the scope of the claim.

What I claim is:—

A hame and trace connector consisting of a sheet metal member having its ends 90 wrapped about each other to form a tubular bearing member and having portions cut therefrom to form arms, the said arms having spaced eyes at the ends thereof and a bolt removably mounted in the said eyes. 95

In testimony whereof, I affix my signature, in the presence of two witnesses.

WILLIAM A. THOMAS.

Witnesses:

W. E. DALEY,
J. E. WELLS.
